United States Patent Office

Des. 195,661
Patented July 9, 1963

195,661

VEHICLE TIRE

Charles G. Wyman, Devon, and Orris H. Johnson, Wayne,
Pa., assignors to Lee Rubber & Tire Corporation, Con-
shohocken, Pa., a corporation of New York

Filed Feb. 25, 1963, Ser. No. 73,709

Term of patent 14 years

(Cl. D90—20)

Fig. 1.

Fig.2.

Fig.3.

FIGURE 1 is a perspective view of a vehicle tire showing our new design;

FIGURE 2 is a fragmentary top plan view thereof; and

FIGURE 3 is a transverse cross-sectional view taken on the line 3—3 of FIGURE 2.

We claim:

The ornamental design for a vehicle tire, as shown.
